W. S. WESTON

DUST COLLAR FOR GYRATORY CRUSHERS

Filed July 18, 1922

Inventor

W. S. Weston,

By *Watson, Tait, Moore & Grindle,*

Attorneys.

UNITED STATES PATENT OFFICE.

WILLIAM S. WESTON, OF COLUMBIA, SOUTH CAROLINA.

DUST COLLAR FOR GYRATORY CRUSHERS.

Application filed July 18, 1922. Serial No. 575,861.

The present invention relates to gyratory crushing machines and particularly to devices for excluding dust and dirt from the socket in which the gyratory shaft is supported.

The crushing shaft of the usual gyratory crushing machine is of large size and great weight and the entire weight of this shaft is supported in a single bearing, located either 10 at the top of the machine or at the bottom. It is essential to provide means for preventing the entrance of dust and dirt into the socket in which the shaft end is mounted inasmuch as such foreign abrasive material will rapidly 15 wear out the shaft end and the walls of the socket, thus causing looseness of the shaft and noise in operation and resulting in the necessity of frequent cleaning or repair.

The object of this invention is to provide 20 a dust excluding device of this character which is particularly adapted to be used with a gyratory shaft which is supported at its lower end. Such a shaft bearing is in certain types of machines, constantly surrounded 25 by clouds of dust and streams of rock and grit falling from the crushing hopper to the reservoir beneath the machine. It is necessary therefore to provide a thoroughly effective means for preventing the 30 entrance of dirt into the shaft supporting socket and one which is durable and capable of standing considerable mechanical shock due to the possible impact of fragments of stone.

The invention may be embodied in different ways and adapted for different forms of machines and in the accompanying drawings one embodiment is illustrated by way of example.

The drawing is a longitudinal section 40 through a gyratory crushing machine of the type described and illustrated in my co-pending application, Serial No. 456,663 filed March 29, 1921, showing the improved dust 45 excluding device incorporated therewith.

The frame 10 of the machine has a central cylindrical portion 11 at its lower end and secured thereto by arms 11' which portion has an axial cylindrical aperture or socket 12 therein to receive the lower end of the gyratory shaft 13. The lower end of this shaft is tapered as shown and fits snugly within the correspondingly tapered recess 14 of a cap 15 which takes all of the wear due to the downward thrust of the shaft and due 50 to its lateral thrust in gyrating. This cap

is removable and replaceable so that when it has become worn a new cap may be placed on the end of the shaft. The cylindrical aperture 12 is provided with a bushing 16 60 which flares both ways from the center of gyration and the cap 15 fits closely within the restricted neck of this bushing. The shaft is supported by an adjustable plug 17 upon the upper surface of which the cap 65 15 rests and is gyrated about a center 18 by means of mechanism at its top which is fully described in my copending application above mentioned, the stone being crushed between the concave 19 of the crushing hopper and 70 the conical mantle 20 rigidly supported on the shaft.

The upper surface 21 of member 11 is annular and horizontally or substantially horizontally disposed. Slidably resting upon this surface 21 is a ring 22 preferably of substantially triangular cross section as shown, this ring having a cylindrical inner surface 23 and a spherical outer surface 24 which is centered about the point 18. A 80 sleeve member 25 is positioned above the ring 22 and is provided with a lower surface 26 which is also spherical and centered about the point 18 so that the surfaces 24 and 26 respectively of the ring and sleeve are in continuous contact with each other. The sleeve 25 has a cylindrical inner surface 27 fitting closely around the cylindrical outer surface of cap 15 and has a concentric cylindrical outer surface 28 which is engaged by the cylindrical inner surface of the downwardly and inwardly turned flange 29 projecting from the upper edge of cap 15. 90

The sleeve 25 is vertically movable relatively to the cap 15 but normally rests on ring 22, fitting tightly against the ring owing to its considerable weight.

The oiling system of the machine includes a pipe 30 for introducing oil under some 100 pressure into the socket in which the lower end of shaft 13 rests. The pressure is sufficient to cause oil to pass upwardly along the cap 15 and to seep out through the joints between the ring 22, and member 11, and 105 through the joints between the sleeve 25, the cap 15, and the ring. It also makes its way into the annular space 31 and seeps out between the cylindrical surface 28 of sleeve 25 and the adjacent annular surface of the 110 flange 29 which fits thereagainst.

In operation the ring 22 will slide lat-

erally upon its supporting surface 21 as the shaft gyrates, the sleeve 25 causing this sliding movement of the ring inasmuch as it positively engages the ring on all sides and 5 moves with the shaft. A sliding movement occurs between the sleeve 25 and ring 22, the spherical surfaces of these members moving relatively a slight distance, and a slight vertical movement of the sleeve 25 relative 10 to the cap 15 will occur. The bearing surfaces are, however, well lubricated in the manner pointed out and substantially no wear takes place between the several parts mentioned. Seepage of oil from the several 15 joints carries away dust which may have collected at the edges of such joints and which might otherwise ultimately make its way in between the bearing surfaces. The flange 29 protects the upper edge of sleeve 25 from 20 the impact of stones falling from the crushing jaws.

It will be seen from the above description that a dust excluding device is provided which is durable and efficient and which is 25 so lubricated that it offers substantially no resistance to the movement of the shaft. To those skilled in the art it will be apparent that the design and arrangement of the several parts of the invention may be modified 30 and that the invention is not limited in its scope to the exact form illustrated and described in detail.

What I claim as my invention and desire to secure by Letters Patent is:

35 1. A gyratory crusher comprising in combination, a frame having a central shaft socket at its lower end and an annular upwardly facing bearing surface encircling the socket, a gyratory shaft having its lower end 40 supported in said socket, means for preventing the entrance of dust and dirt into said socket around the shaft including a ring slidably resting on the annular bearing surface of the frame and encircling the shaft, and a member movable with the shaft and 45 having a dust-tight fit against the ring.

50 2. A gyratory crushing machine comprising in combination, a frame having a central shaft socket at its lower end and an annular upwardly facing bearing surface encircling the socket, a gyratory shaft having its lower end supported in said socket and adapted to gyrate about a point within the 55 socket, means for preventing the entrance of dust and dirt into said socket between the shaft and the wall of the socket including a ring slidably resting on the annular bearing surface of the frame and encircling the shaft, said ring having a spherical upper 60 surface, and a member movable with the shaft and having a spherical lower surface making a dust-tight fit against the ring.

65 3. A gyratory crusher comprising in combination, a frame having a central shaft socket at its lower end and an annular up-

wardly facing bearing surface encircling the socket, a gyratory shaft having its lower end supported in said socket, and means for preventing the entrance of dust and dirt into said socket around the shaft including a ring slidably resting on the annular bearing surface of the frame and encircling the shaft, and a member movable with the shaft and having a dust-tight fit against the ring, said member being mov- 70 75

76 4. A gyratory crusher comprising in combination, a frame having a central shaft socket at its lower end and an annular upwardly facing bearing surface encircling the 80 socket, a gyratory shaft having its lower end supported in said socket, and means for preventing the entrance of dust and dirt into said socket around the shaft including a ring slidably resting on the annular bearing 85 surface of the frame and encircling the shaft, a member movable with the shaft and having a dust-tight fit against the ring, and means secured to the shaft for protecting the upper end of said member. 90

5. A gyratory crusher comprising in combination, a frame having a central shaft socket at its lower end and an annular upwardly facing bearing surface encircling the socket, a gyratory shaft having its lower 95 end supported in said socket, and means for preventing the entrance of dust and dirt into said socket around the shaft including a ring resting on the annular bearing surface of the frame and encircling the shaft, said ring being movable relatively to said shaft and frame, and a member movable with the shaft and having a dust-tight fit against the ring. 100

6. A gyratory crusher comprising in combination, a frame having a central shaft socket at its lower end and an annular upwardly facing bearing surface encircling the socket, a gyratory shaft having its lower end supported in said socket, means for preventing the entrance of dust and dirt into said socket around the shaft and the wall of the socket including a ring slidably resting on the annular bearing surface of the frame and encircling the shaft, a member movable with the shaft and having a dust-tight fit against the ring, and a cap on said shaft having a laterally extending flange to protect the upper end of said member against falling rock. 110 115 120

7. A gyratory crusher including in combination, a frame having a central shaft socket at its lower end, a gyratory shaft having its lower end supported in said socket, means resting on the frame and encircling the shaft for preventing entrance of dust and dirt into the socket around the shaft, and a member rigid with the shaft encircled by said dust excluding means, and having an annular flange portion encircling 125 130

the shaft and positioned above said dust excluding means to protect the same against damage from falling rock.

8. A gyratory crusher including in combination, a frame having a central shaft socket at its lower end, a gyratory shaft, a cap on the lower end of the shaft within the socket and extending upwardly out of the same, said cap having a flange at its upper end with an annular portion transverse to the shaft, and a depending cylindrical portion coaxial with the shaft, and means for preventing the entrance of dust and dirt into the socket around the cap which means includes a cylindrical member slidable longitudinally of the cap, the upper end of which lies under and is protected by the flange of said cap.

9. A gyratory crusher including in com-

bination, a frame having a central shaft socket at its lower end, a gyratory shaft, a cap on the lower end of the shaft within the socket and extending upwardly out of the same, said cap having a flange at its upper end with an annular portion transverse to the shaft, and a depending cylindrical portion coaxial with the shaft, and means for preventing the entrance of dust and dirt into the socket around the cap which means includes a cylindrical member slidable longitudinally of the cap, the upper end of which lies under and is protected by the flange of said cap.

In testimony whereof I hereunto affix my signature.

WILLIAM S. WESTON.
